SHUTTLE CHECK.

APPLICATION FILED FEB. 13, 1915.

1,170,357.

Patented Feb. 1, 1916.

UNITED STATES PATENT OFFICE.

STOGDELL S. STAPLES, OF WHITE HAVEN, PENNSYLVANIA.

SHUTTLE-CHECK.

1,170,357.

Specification of Letters Patent.

Patented Feb. 1, 1916.

Application filed February 13, 1915. Serial No. 7,918.

To all whom it may concern:

Be it known that I, STOGDELL S. STAPLES, a citizen of the United States, residing in White Haven, in the county of Luzerne, State of Pennsylvania, have invented a new and useful Shuttle-Check, of which the following is a specification.

My invention consists of a check for a loom shuttle embodying a resilient device adapted to receive the impact of the picker stick of the loom as a cushion therefor, and means for positively operating from said device, a brake member or binder on the shuttle box of the lay, whereby the shuttle will be stopped and held on the end of its throw at the proper place in said box.

It consists also of means for adjusting the pressure on said member or binder.

It consists also of details of construction as will be hereinafter described and pointed out in the claims.

The invention is satisfactorily illustrated in the accompanying drawing, but the important instrumentalities thereof may be varied, as long as they are included in the scope of the claims.

Figure 1 represents a side elevation of a shuttle check embodying my invention. Fig. 2 represents a partial bottom plan view and partial horizontal section thereof. Fig. 3 represents a vertical section of a portion on the line $x-x$ Fig. 1, on an enlarged scale. Fig. 4 represents a perspective view of a detached portion of the device and Fig. 5 represents a partial side elevation and a partial vertical section thereof, the members in Fig. 4 being separated.

Similar numerals of reference indicate corresponding parts in the figures.

Referring to the drawings, 1 designates the shuttle box of a loom, the same being supported on the lay of the loom as usual, and having the picker stick 2 entering the same from below, as well known. To the underside of said box is secured the bracket 3 on which is pivotally mounted the arm 4 which depends from its axis on the bracket 3 and has a heel 5 between which and said bracket is interposed the spring 6, the same being adapted to be compressed and contracted when said arm is engaged by the picker stick, whereby when said arm is released of said picker stick said spring returns the former to its normal position. The depending member of the arm 4 is directly in the path of the picker-stick 2. Connected

freely with the side of said arm is the bar 7 which is formed of rigid material and extends longitudinally along the box 1 and is connected with the crank arm 8, the latter being secured to the lower end of the rocker or rock shaft 9, which is mounted in vertical direction in bearings 10 on the side of the box 1. Projecting laterally from the shaft 9 is the tongue or brake operating member 11 whose free end is adjacent to the binder or brake member 12 which occupies an opening in the side of the box 1, and in the present instance has an end integrally connected with said side, whereby said member is resilient in its nature, it being noticed that said member is adapted to be forced into the box 1 by the action of the tongue 11 and be placed in the path of a side of the shuttle that is projected into said box by the action of a picker as usual in such cases.

The bar 7 is adjustably connected with the crank arm 8 so as to adjust the degree of oscillation of the latter and the axial end of said crank arm 8 is formed with the serrated collar 13 which is adapted to engage with the serrated collar 14 on the adjacent end of the rock shaft 9 by which provision the degree of rocking motion of said shaft 9 may be adjusted, whereby more or less pressure may be exerted by the tongue 11 on the brake member, and the extent of inward motion of the latter may be adjusted, said pressure being adapted to be exerted on the shuttle that enters the box 1, so that said shuttle will be brought to a gradual stop at the proper time in its box.

When the collars 14 and 13 are separated, the rock shaft 9 may be rotated and so set or adjusted to the required extent. When this is accomplished, the said collars are brought together when their teeth interlock, and the bolt 15 passed through the crank arm and said collars into the rock shaft is tightened, thus retaining said collars connected as one, and securing the crank arm with the rock shaft.

The bearings 10 are formed each of separate members which are connected by the screw 17 which is passed through said members holding the portion of the rock shaft 9 within said members, said portion having a swell or collar 18 which acts as a shoulder assisting in retaining the rock shaft in position, and cause the same to rotate true in

its bearing. The formation of the bearings of separate members or sections admit of the ready displacement and replacement of the shaft from said bearings without necessarily disturbing the other connections of said shaft. The spring 6 is sustained on the bolt 19 which is fitted in the heel 5 of the arm 4 and seated in the adjacent portion of the bracket, said spring being interposed 10 between said bracket and heel as has been stated.

The operation is as follows:—The parts are shown in their normal position on the left end of a lay, and the shuttle thrown 15 by the right hand picker not shown, whereby it enters the left box. Then, the left hand picker receives the impact of the shuttle whereby the picker stitch is thrust against the arm 4 which I now denominate 20 as a check for the picker, and as the picker stick is capable of a slight motion to the left, the arm 4 is thrown back by the same resisted by the spring 6, thus providing a cushion or buffer for the picker stick which 25 resiliently receives the impact of the picker stick and gradually checks the motions of the same to its end. Simultaneously therewith, the bar 7 is drawn back with said arm 4, thus rotating the crank arm 8 and 30 the rock shaft 9, whereby the tongue 11 forces in the brake member 12 and causes the latter to contact somewhat resiliently with the side of the shuttle and serves to 35 slow the motions of the latter, and resiliently stop the same in the box 1 at the proper time. Then as the left hand picker stick has completed its motion, and is ready to move the shuttle to the right, the arm 4 is relieved of said picker stick, when the 40 spring 6 is permitted to expand, which it does, restoring the arm 4 to its normal position, moving the bar 7 to the right, and operating the crank arm 8, the rock shaft 9, and tongue 11 in such manner that said 45 tongue is removed from the brake member 12, when the latter resumes its normal position and withdraws from the shuttle just when the left hand picker is ready to throw the shuttle to the right, the shuttle then 50 being in no wise held or controlled by the brake member and so may be operated immediately to the right.

The inner sides of the separate members or sections of the bearings 10 are tongued 55 and grooved so that said sides interlock and so firmly connect the sections or members when tightened by the screws 17.

The swells or collars 18 are on the exterior of said sections respectively above 60 and below the same as shoulders as hereinbefore stated, said shoulders being adapted to rotate on the bearings, they avoiding reduced necks on the rock shaft which weaken the latter, while on the contrary strengthening 65 said rock shaft and allowing the open-

ings in the bearings to remain truly circular without deepening said openings to receive the swells, thus preserving the strength of the bearings.

Having thus described my invention what 70 I claim as new and desire to secure by Letters Patent, is:—

1. In a check for loom shuttles, a shuttle box, a picker stick, a bracket secured to a part of said box, an arm pivotally mounted 75 on said bracket, a spring bearing against one limb of said arm, and a bar connected with the other limb of said arm and extended for connection with brake mechanism of said check.

2. In a check for loom shuttles, a shuttle box, a picker stick, a bracket secured to a part of said box, an arm pivotally mounted on said bracket, a spring bearing against one limb of said arm, a bar connected with the 85 other limb of said arm and extended for connection with brake mechanism of said check, said spring being compressible when the said arm is engaged by the picker stick.

3. In a check for loom shuttles, a shuttle box, a pivoted arm, a resilient device bearing on a limb of said arm, a bar pivotally connected with said arm, a rock-shaft pivotally connected with said bar, a brake member, and means on said rock-shaft adapted 95 to engage the brake member when said rock-shaft is operated.

4. In a check for loom shuttles, a shuttle box, a pivoted arm having a depending member directly in the path of the picker stick, a spring bearing upon a limb of said arm, a bar pivotally connected with the other limb of said arm, a rock-shaft, means 100 pivotally connecting said rock-shaft and bar, a brake member, and a tongue on said rock-shaft adapted to engage said brake member when said rock-shaft is operated, said bar being adjustably connected with said rock shaft.

5. In a check for loom shuttles, a shuttle box, a pivoted arm on said box having a depending member directly in the path of the picker stick, a bar pivotally connected to said arm between its ends, a rock-shaft, a crank arm pivotally connected with said bar, a brake member, and a tongue on said arm adapted to engage said brake member 115 when the rock-shaft is operated.

6. In a check for loom shuttles, a shuttle box, a pivoted arm on said box having a depending member directly in the path of the picker stick, a spring bearing upon said arm on the opposite side of its pivot, a bar pivotally connected with said arm between its ends, a rock shaft, a crank arm on said rock shaft pivotally connected with said bar, a brake member, and a tongue on said arm adapted to engage said brake member when the rock shaft is turned.

7. In a check for loom shuttles, a shuttle

box, a picker stick entering the same from below, an arm pivotally supported on said box and having a depending member directly in the path of and engageable by the picker stick, a spring engaged by the upper end of said arm and adapted to be compressed when said arm is moved by the picker stick, a bar connected at one end to said arm between its pivot and said depending portion, a crank arm adjustably connected with said bar, a rock shaft, and a brake operating member carried by the latter.

8. In a check for loom shuttles, a shuttle box, a picker stick entering the same from below, an arm pivotally supported on said box and having a depending member directly in the path of and engageable by the picker stick, a spring compressible when said arm is moved by the picker stick, a bar connected at one end to one limb of said arm, a crank arm adjustably connected with said bar, a

rock-shaft, and a brake-operating member carried by the latter.

9. In a check for loom shuttles, a shuttle box, a picker stick entering the same from below, an arm pivotally supported on said box and having a depending member directly in the path of and engageable by the picker stick, a spring compressible when said arm is moved by the picker stick, a bar connected at one end to one limb of said arm, a crank arm connected with said bar, a rock-shaft, a brake member on the shuttle box, a brake operating member carried by the rock-shaft and serrated collars on said crank arm and rock-shaft respectively adapted for variable engagement for the adjustment of said brake operating member with relation to said brake member.
